UNITED STATES PATENT OFFICE.

CLINTON O. HARRINGTON, OF EDGEWOOD BOROUGH, PENNSYLVANIA, ASSIGNOR TO
THE UNION SWITCH & SIGNAL COMPANY, OF SWISSVALE, PENNSYLVANIA, A COR-
PORATION OF PENNSYLVANIA.

SIGNAL.

1,278,838.

Specification of Letters Patent. Patented Sept. 10, 1918.

Application filed January 20, 1914. Serial No. 318,155.

To all whom it may concern:

Be it known that I, CLINTON O. HARRINGTON, a citizen of the United States, residing at Edgewood borough, in the county of Allegheny and State of Pennsylvania, have invented certain new and useful Improvements in Signals, of which the following is a specification.

My invention relates to signals and particularly to signals of the type in which a source of light is employed for giving indications both at night and in daylight. Signals embodying my invention are particularly adapted for use in railway signaling, although their adaptation is not limited to this particular use. When a signal of this type is used on a railway curve, the beam of light projected by the signal should be visible from all points on the curve in the rear of the signal. Hence, this beam is preferably elongated in a horizontal direction, but not in a vertical direction because vertical dispersion would mean wasted light. Furthermore, in order to provide somewhat uniform illumination throughout the curve, the beam is preferably of varying intensity, the portion which is projected toward the points on the curve farthest from the signal being of greater intensity than the portion which is projected toward the points on the curve nearer the signal. One feature of my invention is the provision of a signal which will project an elongated beam of light, different portions of the beam being of different intensities.

I will describe one form of signal embodying my invention and will then point out the novel features thereof in claims.

In the accompanying drawing, Figure 1. is a view showing in front elevation one form of signal embodying my invention. Fig. 2 is a curve showing the intensity of light at different points in the plane II-II of Fig. 1. Fig. 3 is a diagrammatic view showing a railway curve having applied thereto a signal of the form shown in Fig. 1.

Similar reference characters refer to similar parts in each of the views.

Referring first to Fig. 1, the signal here shown comprises a paraboloidal reflector R and a source of light 2, which latter, as here shown, is an electric incandescent lamp. The reflector R is preferably formed of glass, the outside surface of which is silvered as in mirror construction. The reflector and

lamp are, of course, mounted in a suitable framework in such manner that the lamp is located substantially at the focus of the reflector, but to simplify the drawings the framework is omitted.

The reflector R, as here shown, comprises a main section X^c, and seven sections X^d, X^e, X^f, X^g and X^h which are displaced from section X^c in the following manner: Sections X^d, X^e are each displaced a slight amount, preferably by swinging around the focus O as a center and in a direction parallel to line II-II. Sections X^f, X^g are similarly displaced a slightly greater amount. Sections X^f, X^g are similarly displaced a slightly greater amount than sections X^e, and section X^h is similarly displaced a slightly greater amount than sections X^f. Sections X^h are together smaller than section X^c, sections X^e are together smaller than sections X^d, sections X^f are together smaller than sections X^e, and section X^g is smaller than the sum of sections X^f. It will be seen, therefore, that I provide a reflector comprising sections of progressively decreasing size, which sections are displaced in progressively decreasing amounts. The intensity of the light projected from this reflector is substantially as indicated in Fig. 2, from which it will be seen that the rays from section X^c produce a zone C of relatively high intensity adjacent one end of the beam, the rays from sections X^d, produce a zone D of lower intensity next to zone C, and so on down to zone G which is produced by the rays from section X^h and which zone is of the lowest intensity of any part of the beam. In other words, the beam varies progressively in intensity from a maximum value adjacent one end to a minimum value adjacent the other.

Referring now particularly to Fig. 3, B designates a railway curve of 2° curvature, 1500 feet long. Located at one end of this curve is a signal S which is constructed as shown in Fig. 1. This signal is so placed that the rays of light projected from section X^c of the reflector are directed toward portion C of the curve, this portion being the fifth of the curve located at the end farthest from the signal. This part of the beam is of the highest intensity, as indicated in Fig. 2. The rays from sections X^d, X^e are directed toward portion D of the curve, this portion being the fifth of the curve next to

portion C. This part of the beam is of lower intensity, but portion D of the curve is nearer to the signal than portion C, hence the candle-foot illumination on portion D is substantially the same as on portion C so that the light reaching these portions appears to be of substantially the same brilliancy to an observer moving along the curve. Similarly, the rays from sections X^E 10 are projected toward portion E of the curve, those from sections X^F toward portion F, and those from section X^G toward portion G; and since the intensity of light projected from these sections decreases progressively 15 and the portions of the curve progressively approach the signal, the light which reaches all points on the curve appears to be of substantially the same brilliancy to an observer moving along the curve.

20 Although I have herein shown and described only one form of signal embodying my invention, it is understood that various changes and modifications may be made therein within the scope of the appended 25 claims without departing from the spirit and scope of my invention.

Having thus described my invention, what I claim is:

1. A signal comprising a source of light, 30 and a reflector adapted to project a beam from said source, sections of said reflector of progressively decreasing size being displaced at progressively increasing distances from the remainder of the reflector, whereby the 35 beam projected therefrom is elongated and varies progressively in intensity from a max-

imum value adjacent one end to a minimum value adjacent the other.

2. A signal comprising a source of light, and a reflector adapted to project a beam 40 of light from said source, sections of said device of progressively decreasing size being displaced at progressively increasing distances from the remainder of the device, whereby the beam projected therefrom is 45 elongated and varies progressively in intensity from a maximum value adjacent one end to a minimum value adjacent the other.

3. A signal comprising a source of light, and a reflector adapted to project a beam of 50 light from said source, the half of said reflector on one side of a plane passing through its axis being divided into radial sections of progressively decreasing size, and the other half of the reflector on the 55 other side of said plane being symmetrically divided into radial sections of progressively decreasing size, and the said sections on opposite sides of said plane being displaced 60 from the first and largest section in progressively increasing amounts, whereby the beam projected from the signal is elongated in the direction of said plane and varies progressively in intensity from a maximum value at one end to a minimum value at the 65 other.

In testimony whereof I affix my signature in presence of two witnesses.

CLINTON O. HARRINGTON.
